UNITED STATES PATENT OFFICE.

WILLIAM C. BASTIAN, OF NEW YORK, N. Y.

STEM FOR TOBACCO-PIPES.

980,476.

Specification of Letters Patent. Patented Jan. 3, 1911.

Application filed May 7, 1910. Serial No. 560,051.

To all whom it may concern:

Be it known that I, WILLIAM C. BASTIAN, a citizen of the United States, residing at New York, in the county of New York and State of New York, have invented new and useful Improvements in Stems for Tobacco-Pipes, of which the following is a specification.

The present invention relates to pipes.

Its object is to provide a pipe in which the condensed vapors and saliva which naturally collect in the stem, will be prevented from passing to the bowl, and which, together with the products of distillation from the tobacco, will, to a considerable degree, be absorbed.

In order that the invention may be clear to those skilled in the art to which it belongs, I have shown in the accompanying drawings a pipe embodying my invention.

In said drawings—Figure 1 is a view in longitudinal section of a pipe made in accordance with my invention. Fig. 2 is an enlarged view in longitudinal section, of a part of the pipe stem. Fig. 3 is a view in transverse section on line 3—3 of Fig. 2. Fig. 4 is a detail view in elevation, of the porous valve with which the stem is provided, the passages therethrough being shown in dotted lines.

Referring to the drawings by numerals to designate the several parts, like numbers indicating like parts in the several views; 2 designates the bowl of the pipe, which may be of any desired style, shape and material, the particular design of the bowl being of no consequence, as this forms no part of my invention.

Fitted to the stem of the bowl 2 by a slip joint, or in any suitable manner, is a bit, which is shown in the present instance as made up of two parts, namely, the part 4 which is fitted to the bowl-stem 3, and has an enlarged chamber or pocket 5 at its upper end to which the smoke-passage 7 delivers, the upper end of said smoke-passage 7, where it enters said chamber 5, being flared as at 8 to the diameter of the chamber so as to form a valve seat, presently to be described. The said bit member 4 is coupled to a mouth-piece 9 by a screw-thread or other suitable connection 10, the bit 4 being preferably enlarged or swelled at the point of union to give a proper landing or junction of the two separable parts. Said bit mouth-piece 9 is, of course, traversed by a smoke-

passage 11, as is customary, and, as shown, the top wall of the pocket at the lower end of the smoke-passage 11 at the coupling end of the bit member 9 is flat, for a purpose presently to be described. It will be seen that as thus constructed the two-piece bit is provided between its ends with a chamber or pocket to which the smoke passages to and from the bowl delivers, and through which the smoke must pass. In the said pocket 5 is placed a valve member 13, which is of slightly less diameter than the bore of the chamber 5, in order that there may be free passage between the valve member 13 and the wall of the chamber 5. The said valve member 13 has a coned end 14 by preference, and a flat top-face 15, and such coned end seats in the valve-seat formed by the flared section 8 at the point of union of the chamber 5 and smoke passage 7, so as to normally close such passage 7. The said valve member 13 is preferably made of a light absorptive substance, such, for example, as meerschaum, and at a point removed from its lower end is provided with one or more transverse passages or perforations 16, which connect with one or more passages 17 extending to the upper end of the valve member; the arrangement shown resulting in a cruciform smoke passage with the vertical passage trapped at its lower end. The said valve member 13 is slightly shorter than the chamber 5 in which it is seated, so that it has a slight play back and forth in the chamber 5 to close and open a passage above the flared valve-seat 8 at the upper end of smoke passage 7.

When the pipe is in use, the said valve member 13, being of light material, will respond to suction on the bit, and lift, raising its coned end 14 from the seat 8 and allowing the smoke to come from the bowl 2 by stem 3 and bit member 4 to chamber 5; this lifting of the valve member 13 at the same time seating its upper flat end 15 against the inner flat wall 12 of the bit-member 9, so that smoke coming from the passage 7 to chamber 5 can only pass to the passage 11 in bit-member 9 by traversing the passages 16 and 17 in the valve member 13. The result of this is that the smoke, prior to reaching the mouth of the smoker, must traverse passages in the absorbent valve-member 13, and in passing through the passages the hygroscopic character of the material of which said valve member 13 is

- made will absorb and eliminate from the smoke the bulk of the liquid constituents held in suspension therein.
- When suction ceases on the pipe the valve member 13 will drop to its closed position with its coned end 14 seated in the flared section 8 of the bit member 4, and this will effectually close the smoke-passage 7 and prevent any of the liquid of condensation which may have collected in the smoke passages, or any saliva from the mouth of the smoker from passing to the bowl 2; but hold it in chamber 5 and passage 17 to be absorbed by the valve member 13.
- It will be understood that the valve member 13 may be renewed from time to time as it becomes saturated and foul, as these valve members may be produced at a slight cost and readily inserted.
- It is obvious that material other than meerschaum may be used to make the valve member, as the only requisite is that a comparatively light and absorbent substance be provided. Furthermore, it will be apparent that the disposition, size, and shape of the chamber, the valve-member, and in fact, all of the parts, may be varied; as this is a matter of fancy and design and in no way a departure from my invention, which is not limited, except insofar as it is limited by the terms of the appended claims to the details of the present illustrative disclosure.
- I claim:
1. A pipe having a chambered bit, and a valve in said chamber having smoke-passages therein and normally closing the smoke-passage in said bit.
  2. A pipe having a chambered stem, and a valve in said chamber having transverse and longitudinal smoke-passages therein and normally closing the smoke-passage in said bit.
  3. A pipe having a chambered bit, and a valve in said chamber having a longitudinal passage extending partially therethrough, and a transverse passage entering said longitudinal passage; said valve normally closing the smoke-passage in said bit.
  4. A pipe having a chambered bit, and a valve in said chamber closed at one end and having a smoke-passage therein which delivers at the other end.
  5. A pipe having a chambered bit, and a valve closed at one end and having interconnected transverse and longitudinal smoke-passages which deliver at the other end.

6. A pipe having a chambered bit, and a valve in said chamber having a trapped smoke-passage delivering at one end thereof. 60

7. A pipe having a chambered bit, and a valve in said chamber having a cruciform smoke-passage therein delivering at one end thereof.

8. A pipe having a chambered bit, and a valve in said chamber having a cruciform smoke-passage therein which is trapped at one end and delivers to the bit passage at the other end. 65

9. A pipe having a chambered bit, a valve in said chamber having a trapped longitudinal passage and a transverse passage passing diametrically through said valve and intersecting said longitudinal passage. 70

10. A pipe having a chambered bit provided with a coned valve-seat at its lower end, a coned valve seated therein and normally closing the smoke passage in said bit, a cruciform smoke-passage in said valve delivering at the top thereof, said valve having a flat top seating snugly about the smoke passage when the valve is raised so as to confine the smoke to the bit passage. 75

11. A pipe having a chambered bit, a valve in said chamber formed of absorbent material and having a tortuous smoke passage therethrough, said valve having a closed lower end which normally closes the smoke passage in the bit and having an open upper end which delivers to the smoke passage 90 in the bit.

12. A pipe having a chambered bit, a valve of absorbent material loosely fitting said chamber and having a tortuous passage therein, said valve having a closed lower end 95 which normally closes the smoke passage in the bit, and an open upper end which delivers to the smoke passage in the bit.

13. A pipe having a chambered bit, a valve of less length than the chamber 100 mounted therein and provided with a tortuous smoke passage therein, said valve having a closed lower end which normally closes the smoke passage in said bit, and an open upper end which delivers to the smoke passage in the bit. 105

In testimony whereof I have heretunto set my hand in presence of two subscribing witnesses.

WILLIAM C. BASTIAN.
